UNITED STATES PATENT OFFICE.

THOMAS LARSON, OF BRICELYN, MINNESOTA.

WRENCH.

No. 877,571.

Specification of Letters Patent.

Patented Jan. 28, 1908.

Application filed June 14, 1907. Serial No. 378,941.

To all whom it may concern:

Be it known that I, THOMAS LARSON, a citizen of the United States, residing at Bricelyn, in the county of Faribault and State of Minnesota, have invented certain new and useful Improvements in Wrenches; and I do hereby declare the following to be a full, clear, and exact description of the invention, such as will enable others skilled in the art to 10 which it appertains to make and use the same.

My invention has for its object to provide an improved wrench for applying and removing fusible safety plugs, such as are generally 15 used in connection with threshing machine engine boilers, and to this end it consists of the novel devices and combinations of devices hereinafter described and defined in the claims. As is well known, these safety plugs 20 are usually applied to the crown sheet or top plate of the fire box where they cannot be reached by ordinary means when there is fire within the fire box or when the fire box is hot. Hence, in practice, it very frequently happens that much time is wasted when one of 25 these fusible plugs is burned out, because a person cannot enter the fire box and replace the plug until after the fire is put out and the fire box cooled off.

30 My invention provides a very simple and convenient device by means of which one of these plugs may be removed and another replaced without waiting for the fire box to cool off and, in fact, without putting out the 35 fire.

In the accompanying drawings which illustrate the improved device, like characters indicate like parts throughout the several views.

40 Referring to the drawings; Figure 1 is a plan view of the improved wrench. Fig. 2 is a vertical longitudinal section taken through the wrench on the line $x^2 x^2$ of Fig. 1. Fig. 3 is an end elevation of the wrench looking at 45 the same from the right toward the left with respect to Figs. 1 and 2; and Fig. 4 is a transverse section taken on the line $x^4 x^4$ of Fig. 2.

The wrench socket or plug engaging head 1 of the wrench is secured to a short shaft 2 50 that is journaled in a bearing yoke 3 and is provided with a bevel gear 4. The bevel gear 4 meshes with a bevel gear 5 that is carried by a long driving shaft 6, the inner end of which is journaled in a suitable bearing sleeve 7 on said yoke 3. The shaft 6 extends 55 preferably, as shown, at an angle of ninety

degrees to the shaft 2. The body of the shaft 6 is extended through a long tube or sleeve extension 8, the inner end of which is shown as screwed into the sleeve 7 so that it is thereby rigidly secured to the bearing yoke or head 3. At its extreme outer end, the shaft 6 is provided with a hand operated crank 9 by means of which the said shaft 6 and hence the shaft 2 in the socket 1 may be 60 rotated at will in either direction. A hand piece 10 is rigidly secured to the tube 8 near its outer end.

On the tube 6, some little distance from the bearing yoke 3, is a split collar 11 to the 70 prongs of which is pivotally attached the tubular member 12 of an extensible supporting leg; the extensible member 13 of which is provided at its lower end with a bearing foot 14. The leg member 13 is in the form of a 75 rod that is telescoped into the tubular member 12 and is adapted to be held in any adjustment in respect thereto, as shown, by a set screw 15 screwed through a seat in one side of said member 12. The lug in the upper end of the member 12, which is clamped between the prongs of the split collar 11 by a bolt 16, is rounded on one side so that the extensible leg is adapted to be bolted or moved pivotally, but is provided with a stop 80 shoulder 17 at its other side which limits the movement of the extensible leg toward the crank 9 to a position approximately at a right angle to the shaft 6.

In using the wrench above described, the 90 extensible leg 12-13 should be so adjusted that when rested upon the grate or upon material detained upon the grate, will serve as a support or fulcrum over which the sleeve or tube 8 may be rocked to force the socket 95 1 inward and thereby hold the same in engagement with the plug that is to be applied or removed from working position in the crown sheet or fire box. When the wrench is thus applied and held with one hand applied to the hand piece 10 and the other applied to the crank 9, it is evident that the socket 1 may be readily rotated in either direction as is required to apply or remove the plug.

It is sometimes desirable to support the 105 wrench from the flue sheet of the boiler, and when this is to be done the extensible leg may be moved pivotally against the bearing yoke 3 and the foot 14 thereof engaged with the ends of the flue, so that the latter will 110 then serve as a base of support for the wrench. To better adapt the foot 14 for

application to the ends of the flues, it may be provided with projections 14^a that will adapt it to enter the ends of the flues; or, if desired, a simple straight rod may be substituted for the leg section 13.

The device described, while simple, is highly efficient for the purposes had in view, and by its use very great saving in time, not only of the person using the same but with an entire threshing crew, may be accomplished.

What I claim is:

1. In a wrench of the kind described, the combination with a gear supporting head having a long extended bearing, of a long driving shaft journaled in said extended bearing and provided at its outer end with means for rotating it, a relatively short shaft journaled in said head extending at an angle to the said driving shaft and provided at one end with a wrench socket or head, gears connecting the said two shafts, and a supporting leg applied to the intermediate portion of said extended shaft, substantially as described.
2. In a wrench of the kind described, the combination with a gear supporting head, a long sleeve extension provided at its extended end with a hand piece, a long driving shaft journaled in said sleeve and provided at its outer end with an operating crank, a relatively short shaft journaled in said head extending approximately at a right angle to said driving shaft and provided at one end with a wrench socket, bevel gears connecting

said two shafts, and a supporting leg applied to the intermediate portion of said sleeve, substantially as described.

3. In a wrench of the kind described, the combination with a gear supporting head having a long sleeve provided at its extended end with a hand piece, a driving shaft journaled in said sleeve and provided at its extended end with an operating crank, a relatively short shaft journaled in said supporting head and provided at one end with a wrench socket, gears connecting said two shafts, and an extensible supporting leg applied to the intermediate portion of said sleeve, substantially as described.

4. In a wrench of the kind described, the combination with a gear supporting head having a long extended sleeve, a driving shaft journaled in said sleeve and provided at its outer end with an operating crank, a relatively short shaft journaled in said supporting head and provided at one end with a wrench socket, gears connecting said two shafts, and a longitudinal telescopic extensible supporting leg pivotally connected to the intermediate portion of said sleeve, substantially as described.

In testimony whereof I affix my signature in presence of two witnesses.

THOMAS LARSON.
